PROCESS OF COKING

Application filed July 28, 1928. Serial No. 296,046.

This invention relates to a process of coking coal tar, pitch, heavy petroleum residues and other liquid or liquefiable hydrocarbons of a similar nature. These compounds are 5 hereinafter termed "heavy liquid hydrocarbons". They are all liquid when subjected to our process of distillation, although they may be viscous or solid at ordinary temperatures. If mixed with gas containing oxygen 10 they will not ordinarily form explosive mixtures. In carrying on such process, in order to realize the greatest value from the products thereof, it is a common practice to start with a simple distillation at a comparatively 15 low temperature and to gradually increase the temperature until a destructive distillation takes place, which finally leaves coke as a residue. Heretofore, the distillation has usually been effected by means of heat di- 20 rected against the bottom or sides of a chamber containing the compound to be distilled. This makes it essential for the chamber walls to be made from material having a high heat conductivity, steel being the most practical. 25 As the distillation approaches the ultimate stage, the reaction becomes exothermic, thus increasing the difficulty of controlling the temperature within the chamber. In the de- 30 structive distillation of a liquid mass, this difficulty is greatly magnified, due to the fact that the entire mass has substantially a uniform temperature and reaches the critical point all at once.

In using such a process, therefore, even 35 when the utmost care is exercised, it is inevitable that the steel walls soon deteriorate and become distorted, and it becomes necessary to repair them or to replace them alto- 40 gether at a considerable expense.

Various attempts have been made to over- 45 come the above mentioned difficulties by applying the heat in successive stages to different parts of the chamber, or by using a succession of chambers in which various stages of the distillation take place, but such varia- 50 tions of the process above described have involved a great deal of expense in the construction of the apparatus and have proved very wasteful of the heat used for the purpose.

With the above conditions in mind, it is an

object of our invention to provide an im- 55 proved process, which is particularly adapted to the coking of heavy liquid hydrocarbons and which may be carried to its ultimate con- 60 clusion without excessive injury to or de- 65 terioration of the apparatus used. Our proc- 65 ess also has a very high thermal efficiency, since the products of combustion, which de- 70 velop the heat, are delivered directly into the liquid mass and bubble up through the same, 75 so that the heat is transmitted directly there- 80 to without appreciable loss. The walls of the chamber containing the mass to be distilled may be lined with inexpensive, highly re- 85 fractory, heat insulating material. By con- 90 trolling the draft, the degree of heat in the mass may be controlled with the utmost pre- 95 cision.

Our invention will be more particularly 70 explained in connection with the accompany- 75 ing drawing, which represents diagrammati- 80 cally one form of apparatus which may be 85 used in carrying out the process.

In the drawing, the numeral 1 indicates 75 a closed chamber which is adapted to receive 80 the material to be distilled. This chamber may be formed with an outer wall 2 of steel, which is lined with fire brick 3 or other suit- 85 able refractory material. The heat for ef- 90 fecting the coking is supplied by a furnace 4, 95 in which coal, coke or other suitable fuel may be burned. The products of combustion in the furnace 4 pass through a flue 5, which may be provided with an outlet 6 for con- 100 venience in starting the fire and for maintain- 105 ing the same when the process is not in pro- 110 gress.

In proceeding with the process, after the 115 chamber 1 has been charged, the outlet 6 is closed by means of a valve or damper 7, and 120 the products of combustion in the furnace 4 pass through a pipe 8, which extends down- 125 wardly through the top of the chamber 1 and into the liquid mass, discharging the hot gases directly into contact with the same near the 130 bottom of the chamber 1, so that they bubble 135 up through the mass and leave the chamber 1 through a pipe 9 connected with the top 140 thereof.

The pipe 9 leads through a condenser 10, 145

of any suitable type, and thence to a receiver 11, where the distillate may be collected and drawn off from time to time through an outlet cock 12. A window 13 may be provided between the condenser 10 and the receiver 11, so that the progress of the distillation may be observed.

As the volatilized portions of the liquid mass in the chamber 1 are condensed and collected in the receiver 11, the original products of combustion in the furnace 4, which are gaseous at ordinary temperatures, are carried away through a pipe 14 leading to a suction pump, which is operated continuously during the process of distillation, to maintain an induced draft from the furnace 4 through the apparatus. The process may be continued until there is nothing but coke left in the chamber 1. This chamber may be provided with a bottom 15 arranged in any suitable manner so that it may be opened in order to remove the coke residue.

In this process, all of the heat produced by the combustion of the fuel is transmitted into direct contact with the liquid mass to be distilled, without any appreciable loss. Any unburned portion of the fuel which is carried over into the chamber 1 will be of the same nature as the material in the chamber 1 and will be subject to the same process of distillation. The metallic portion of the walls of the chamber 1 will be protected from the heat and will last indefinitely without material deterioration. The temperature within the chamber 1 may be controlled with the utmost accuracy by regulation of the pump by means of a valve in the line 14 or by the adjustment of the valve 7. The process may be continued with the utmost efficiency and economy until an exothermic reaction takes place and nothing but low volatile coke is left in the chamber 1.

The valve 7 will be of special utility during the final stage of the process. By opening this valve air will be admitted from the flue 6 directly into the chamber 1, thus oxidizing the small proportion of hydrocarbons remaining therein, with a resultant hardening of the coke residue, which will, in fact, be fully as hard as beehive coke. By this arrangement it will be seen that oxidizing the portions of the hydrocarbons remaining in the chamber 1 results in the utilization of the entire residue to form coke, without the necessity of transferring any portion of the mass operated on from one container to another. That is to say, after liquid hydrocarbon has been placed in the chamber 1 at the start of the process, the same remains therein until the process is completed and the final product, coke, is removed. During this last stage of the process the introduction of the combustion gases into the batch practically ceases. Of course the volume of air admitted will be so controlled that there will

not be any appreciable oxidation of the coke residue.

While we have illustrated diagrammatically one form of apparatus by which our improved process may be carried out, it is to be understood that this is merely for the purpose of illustration, and that the sizes, proportions and arrangement of the various parts thereof may be modified to a considerable extent, without any alteration of the principles embodied in the process. It is obvious that, instead of using a suction pump to create the induced draft, a blower may be used in connection with the furnace.

What we claim is:

1. The process of coking which comprises destructively distilling a batch of a heavy hydrocarbon liquid to a hard low volatile coke by conducting hot gases produced by the combustion of carbonaceous fuel, under induced draft, into the batch of liquid and liberating the same near the bottom thereof, and allowing said gases to bubble up through said liquid.

2. The process of coking which comprises destructively distilling a batch of a heavy hydrocarbon liquid to a hard low volatile coke by conducting hot gases produced by the combustion of carbonaceous fuel, under induced draft, into the batch of liquid and liberating the same near the bottom thereof, allowing said gases to bubble up through said liquid, and condensing the distillate thus produced.

3. The process of coking which comprises destructively distilling a batch of a heavy hydrocarbon liquid to a hard low volatile coke by conducting hot gases produced by the combustion of carbonaceous fuel, under induced draft, into the batch of liquid and liberating the same near the bottom thereof, allowing said gases to bubble up through said liquid until an exothermic reaction takes place and condensing the distillate thus produced.

4. The process of coking which comprises destructively distilling a batch of a heavy hydrocarbon liquid to a hard low volatile coke by conducting hot gases produced by the combustion of carbonaceous fuel, under induced draft, into the batch of liquid and liberating the same near the bottom thereof, and allowing said gases to bubble up through said liquid until the batch is substantially reduced to coke, and then introducing air into the residue and liberating the same near the bottom thereof to oxidize the small proportion of hydrocarbons remaining therein.

5. The process of coking which comprises destructively distilling a batch of coal tar to hard low volatile coke by conducting hot gases produced by the combustion of carbonaceous fuel, under induced draft, into the batch of tar and liberating the same near the

bottom thereof, and allowing said gases to bubble up through the tar.

6. The process of coking which comprises destructively distilling a batch of coal tar to a hard low volatile coke by conducting hot gases produced by the combustion of carbonaceous fuel, under induced draft, into the batch and liberating the same near the bottom thereof, allowing said gases to bubble up through the tar and condensing the distillate thus produced.

7. The process of coking which comprises destructively distilling a batch of coal tar to a hard low volatile coke by conducting hot gases produced by the combustion of carbonaceous fuel, under induced draft, into the batch and liberating the same near the bottom thereof, allowing said gases to bubble up through the tar until an exothermic reaction takes place and condensing the distillate thus produced.

8. The process of coking which comprises destructively distilling a batch of coal tar to a hard low volatile coke by conducting hot gases produced by the combustion of carbonaceous fuel, under induced draft, into the batch of tar and liberating the same near the bottom thereof, and allowing said gases to bubble up through the tar until the batch is substantially reduced to coke, and then introducing air into the residue and liberating the same near the bottom thereof to oxidize the small proportion of hydrocarbons remaining therein.

35 In testimony whereof we have hereunto signed our names to this specification.
